(57) **CLAIM**

The ornamental design for a connecting tool for evaporator, as shown and described.

DESCRIPTION

FIG. 1 is a top, left, front perspective view of a connecting tool for evaporator, showing my design;

FIG. 2 is a top plan view thereof;

FIG. 3 is a front elevational view thereof;

FIG. 4 is a bottom elevational view thereof;

FIG. 5 is a rear elevational view thereof;

FIG. 6 is a right side elevational view thereof; and,

FIG. 7 is a left side elevational view thereof.

All broken lines shown in FIGS. 5 and 7 form no part of the

design of the present invention.
